UNITED STATES PATENT OFFICE

2,107,861

CORRUGATED WALL FOR RAILWAY CARS

Garth G. Gilpin, Riverside, Ill., assignor, by
mesne assignments, to Standard Railway
Equipment Manufacturing Company, a corpora-
tion of Delaware

Application November 4, 1936, Serial No. 109,074

4 Claims. (Cl. 105—410)

The invention relates to end walls for railway freight cars which are made of metallic sheets formed with a plurality of parallel corrugations which function as a series of beams to transmit 5 any horizontal load imposed thereon by shifting lading to the corner post or side wall of the car.

Applicant's assignee promotes and sells car end walls, as shown in Patents No. 1,681,811, and No. 1,681,812 of August 21, 1928, and it has been found 10 that such ends having the divided or split corrugations cannot commercially and economically be produced in thin metallic sheets because the terminations of the corrugations tear in the pressing operation and the metal adjacent the terminations buckles to such an extent that it is difficult 15 to secure a waterproof attachment of the car end to the car structure. Even greater difficulties have been experienced in forming such corrugated end walls of some of the new non-corrosive 20 steel sheets.

One of the objects of the invention is to form 25 a relatively thin metallic sheet with a plurality of substantially parallel corrugations which extend to the opposite edges of the sheet and to provide relatively thin corner post members which provide 30 means of attaching the corrugated metallic sheet to the car structure. Such corner posts also provide means to effectively continue the corrugations beyond the edges of the sheet so as to continue and extend the beam effect of the corruga- 35 tions. My invention is an improvement upon the structure shown in Patent No. 1,236,744 of August 14, 1917.

Another object of the invention is to provide 40 means to secure a corrugated metallic sheet to the corner post member or members so as to form a waterproof construction therebetween.

Another object is to form a corner post of two 45 cooperating members, one of which provides an effective means of welding the other member to the corrugated sheet.

In the drawing:

Fig. 1 shows an end of a railway car equipped 50 with an end wall according to my invention.

Fig. 2 is an enlarged section on line 2—2 of 55 Fig. 1.

Fig. 3 shows a modification of my invention.

Fig. 4 shows a section on line 4—4 of Fig. 2.

In the drawing the usual parts of the car are 60 shown, such as end sill 2, roof 3, push pole pocket 4, striking casting 5, top corner piece 6, running board 7, side sheathing 8, inside side lining 9, inside end lining 10, frame member 11 and nailing strip 12.

The metallic sheet 13 is formed with a plurality 65

of substantially parallel corrugations, such for instance, as shown in elevation in Fig. 1. These corrugations extend to opposite edges of the sheet. An outer corner post and an inner corner post of material which is preferably thicker than the 5 metallic sheet 13 are provided to secure the corrugated metallic sheet to the side sheathing 8 or other part of the side wall. Each of the posts comprise two angularly disposed arms with one of the arms (16—17) of each post riveted (19) to 10 the side sheathing 8 and frame members 11 and the other arms (20—21) of both of the posts overlapping the inside and outside respectively of the marginal edge of the corrugated sheet. One or both of the arms 20 and 21 are bent to conform to 15 the contour of the corrugated sheet.

The arms 20 and 21 may be riveted to the corrugated sheet, but I preferably weld them to the sheet by providing a continuous weld at 25 to secure the outer arm 21 to the corrugated sheet and 20 spot or intermittent weld (shown at 26) to secure the inner arm 20 to the corrugated sheet. In this arrangement the outer continuous weld 25 forms a waterproof construction and the inner weld 26 cooperates with the outer weld to continue the beam 25 effect of the corrugations to the attaching flanges 16 and 17 which are in the plane of the anchorage of the beams. The arm 20 of the inner post preferably extends beyond the outer arm to provide a shoulder as a backing for the welding operation. 30

Fig. 3 shows a modification wherein the corrugations in both of the corner posts 30 and 31 extend around the corner of the car and merge into the arms 32—33. Such an arrangement stiffens 35 the corner of the car.

The accompanying drawing illustrates the preferred form of the invention, though it is to be understood that the invention is not limited to the exact details of construction shown and described, as it is obvious that various modifications there- 40 of, within the scope of the claims, will occur to persons skilled in the art.

I claim:

1. In a railway car, the combination of a car 45 side wall, a metallic sheet formed with a plurality of substantially parallel corrugations extending to one edge of the sheet, an outer corner post and an inner corner post, each comprising two angularly disposed arms, certain of said arms attached to said side wall and the other arms thereof overlapping the inside and outside respectively of said sheet adjacent said edge, and means to secure the last mentioned arms to said sheet, both of said last mentioned arms conforming to the contour of the corrugated sheet, the arm which overlaps the in- 50 55

side of the sheet being longer than the arm which overlaps the outside of the sheet to form a backing for welding.

- 5 2. In a railway car, the combination of a car side wall, a metallic sheet formed with a plurality of substantially parallel corrugations extending to one edge of the sheet, an outer corner post and an inner corner post, each comprising two angularly disposed arms, certain of said arms attached to said side wall and the other arms thereof overlapping the inside and outside respectively of said sheet adjacent said edge, the inner edge of the outside arm being continuously welded to the sheet for waterproofing and the inner edge of the 15 inside arm being intermittently welded to the sheet, the arm which overlaps the inside of the sheet being longer than the arm which overlaps the outside of the sheet to form a backing for the welding, the arm which overlaps the outside of the sheet being corrugated to conform to the corrugations in the sheet, the corrugations in the outer corner post extending around the corner of the car and merging into the arm of said post which is attached to the side wall.
- 20 25 3. In a railway car, the combination of a car side wall, a metallic sheet formed with a plurality of substantially parallel corrugations extending to

one edge of the sheet, an outer corner post and an inner corner post attached to said side wall, said posts having portions overlapping the inside and outside, respectively, of said sheet adjacent said edge, said portions conforming to the contour of the corrugated sheet, the portion which overlaps the inside of the corrugated sheet being longer than the portion which overlaps the outside of the corrugated sheet to form a backing for welding, and welded material securing the edge of said outer portion to the corrugated sheet. 10

4. In a railway car, the combination of a car side wall, a metallic sheet formed with a plurality of substantially parallel corrugations extending to one edge of the sheet, an outer corner post and an inner corner post attached to said side wall, said posts having portions overlapping the inside and outside, respectively, of said sheet adjacent said edge, said portions conforming to the contour of the corrugated sheet, the portion which overlaps one side of the corrugated sheet being longer than the portion which overlaps the other side of the corrugated sheet to form a backing for welding, and welded material securing the edge of said shorter portion to the corrugated sheet. 15 20 25

GARTH G. GILPIN.
